ELECTRIC FUSE

Edgar W. Garrison, Jr., Birmingham, Ala., assignor to Southern States Equipment Corporation, a corporation of Alabama

Substituted for abandoned application Serial No. 370,261, December 16, 1940. This application January 1, 1942, Serial No. 425,363

8 Claims. (Cl. 200—114)

One of the purposes of the invention is to provide a type of electric fuse suitable for service at high voltage which will operate more certainly and easily than fuses of other designs, which will be free from excessive arcing and which will impose a minimum strain on the fuse link even under rough handling. The specification and claims further explain the purposes of the invention.

Referring to the drawings, Fig. 1 shows a side view of one design of use, in closed circuit position, in which my invention is embodied; Fig. 2 is similar but with the device in partly open position; Fig. 3 is a bottom view of the latch-hood numbers in larger scale; Fig. 4 is a side view of the latch; Fig. 5 shows the hinge members when the device is opened; and Figs. 6 and 7 show two views of one of the many variations which may be made in designs embodying the invention.

The support 1 carries the insulators 2, 3 upon which are mounted the top casting 4 and the hinge casting 5, line connections being made at 20 and 1. The removable expulsion-tube 8 contains the fuse-link 9 the cable-ends of which are secured to the hinge terminal 10 and the latch 11. The latch 11 is pivoted at 12 to the top terminal 13, and the cylindrical surface of 1 makes contact with the spring contact finger 1, which is fastened to the top casting 4. The 30 axis of the cylindrical surface on 11 and the pivot 12 are preferably coincident.

A somewhat similar finger 15 is secured to the hinge casting 5 and makes contact with terminal 10. The trunnions 16 are flattened on one side, so that they can be lifted out of the hinge 5 only when the tube 8 is in the open position indicated by dotted lines in Fig. 2, and shown also in Fig. 5.

The latch 11 has two side projections 17. These are engaged by the lower ends of the ridges which extend inwardly along the lower edges of the latch-hood 19 which is pivoted at 20 to the top casting 4, and which is biased downwardly by the spring 21. A suitable stop limits the downward motion of the hood 19. A spring 45 biases the latch 11 upwardly towards the position shown in Fig. 2 and Fig. 4.

When in closed circuit position shown in Fig. 1, the trunnion 16 is locked against lifting 50 upwardly out of its bearings in the base 5, and the upward pressure of contact finger 15 against the solid hinge terminal 10 biases the tube 8 upwardly away from its closed circuit position. The sides of hood 19 rest against top casting 4, shown in Fig. 3, and limit the downward motion 55

of hood 19. The finger 14 presses outwardly against latch 11 and so holds the projections 17, 17 securely against the ridges 18. There is neither upward nor downward pressure exerted 5 against any part of latch 11 by any member supported on insulator 2. The point of contact between finger 14 and latch 11, the projections 17 and the pivot 12 are all substantially the same radial distance from the pivot at trunnions 16, and an external force tending to pull the tube 8 open would therefore exert no increased pull upon the fuse-link 9; nor does the pressure of finger 14 nor the holding pressure of 18 against 17 tend to rotate the latch 11, but it is rotated 15 solely by the spring 22 after the fuse-link has ruptured.

Operation is as follows: When the fuse-link ruptures at 9 due to overload, the spring 22 swings the latch 11 and the upper half of the fuse-link cable upwardly. As the latch pivots about the pin 12, the cylindrical surface of the latch remains in sliding contact with the finger contact 14 until the projections 17 have become disengaged from the ridges 18. At the same 25 time the cable end is jerked upwardly and a wide gap is established in the circuit within the tube 8, which aids the arc expulsion effect. With 17 disengaged from 18, the pressure from the fingers 14 and 15 tends to rotate the tube 8 around its trunnions 16, and the tube starts its downward swing towards the fully opened position indicated by dotted lines in Fig. 2.

When the fuse is to be replaced, the tube is removed from its hinged support, a new fuse-link is properly installed, the inverted tube is replaced in its hinges and the tube is swung outwardly and upwardly. Thereupon the trunnions become held by the hinge member 5 so that pressure from the contact finger 15 does not dislocate the hinge joint.

As the projections 17 engage the under surfaces of the two ridges 18, the whole hood 19 is raised, against the bias of spring 21, until the projections 17 have reached the ends of ridges 18. Then the hood 19 snaps downwardly and the ridges 18 then hold the device in closed-circuit position as shown in Fig. 1. Meanwhile the finger 14 has been forced inwardly, and in closed-circuit position 18 exerts considerable pressure against the cylindrical surface of latch 11.

Whenever it is desired to open the device manually, the hood 19 is lifted by suitable insulated means. This lifts the ridges 18 up above the projections 17, and pressure from the spring

fingers 14 and 15 swing the tube 8 outwardly so that it immediately drops by gravity to the fully opened position.

The parts are so proportioned that the pressure of the spring finger 14 and the holding effect of the ridges 18 against the projections 17 produce a resultant force that does not tend to rotate the latch 11 around its pivot 12. This is partly due to having the plane of contact between 14 and the cylindrical surface of 11 closely adjacent to the pivot 12. Another factor is that, as seen in Fig. 1, the contact between the finger 14 and the cylindrical surface of 11, the contacts between the projections 17 and the ridges 18, and the axis of the pivot 12, are all closely adjacent to a single plane that is substantially perpendicular to a plane that passes through the axis of the hinge at 16 and the axis of the pivot 12. In normal use the parts are not lubricated and therefore friction will counterbalance the effect of slight variations from the proportions as described.

Thus, even if the tube is violently closed in and there is a consequently hard reaction outwardly, there is no serious strain tending to rotate 11 about its pivot 12. Therefore there is no excessive strain tending to break the fuse-link 9. Substantially the only strain upon the fuse-link 9 is that imposed by the spring 22. This means of reducing the shock on the fuse-link is one of the important features of this invention. Another advantage of this design is that even though sleet might freeze the hood 19 against motion about its pivot 20, the latch 11 could still rotate and so release the tube 8 from its closed circuit position.

A modified design which still includes this invention is shown in Figs. 5 and 6, where the hood 23 carries the fork 24 which is pivoted at 25 and is biased downwardly by the spring 26. Suitable stops limit the travel of the fork 24. Operation is similar to that of the other design, except that, as the fused tube is being closed, the fork 24 rotates about pivot 25 without the necessity of motion of the hood 23 about its pivot.

Other modifications also may be made by one familiar with the art without departing from the spirit and purpose of the invention.

I claim:

1. In an electric fuse, two spaced insulated terminals, an expulsion fuse tube held by a pivotal mounting upon one of said terminals and held by a latch mechanism in contact with the other said terminal, and a fuse-link within the tube and completing the circuit therethrough; the said latch mechanism including a terminal member supported on the said other terminal and a movable member supported movably upon the said fuse tube, these said latch members when in normal closed circuit position engaging one another only by pressure substantially transverse to the length of the tube, and the said pressure exerting substantially no strain on the said fuse link.

2. In an electric fuse, two spaced insulated terminals, an expulsion fuse tube held by a pivotal mounting upon one of said terminals and held by a latch mechanism in contact with the other said terminal, and a fuse-link within the tube and completing the circuit therethrough; the said latch mechanism comprising a latch piece pivotally mounted upon the fuse tube, a spring which biases the latch piece to rotate about its pivotal mounting towards its releasing position, the said rotation being prevented by

tension on the fuse-link, a contact surface on the latch piece substantially cylindrical about its pivotal mounting, a spring contact member biased outwardly against the said cylindrical contact surface, and a holding member on the other said terminal cooperable to engage the said latch piece.

3. In an electric fuse, two spaced insulated terminals, an expulsion fuse tube held by a pivotal mounting upon one of said terminals and held by a latch mechanism in contact with the other said terminal and a fuse-link within the tube and completing the circuit therethrough; the said latch mechanism including a latch piece mounted by a pivot upon the fuse tube and with two lugs which project outwardly beyond the said pivot, a protective hood above the latch piece supported by the said terminal and with parts engageable with the said two lugs to hold the fuse in closed circuit position.

4. In an electric fuse, two spaced insulated terminals, an expulsion fuse tube held by a pivotal mounting upon one of said terminals and held by a latch mechanism in contact with the other said terminal, and a fuse-link within the tube and completing the circuit therethrough and holding a latch piece in normal position; the said latch mechanism including the said latch piece which is pivotally mounted upon the fuse tube and has a holding lug, a spring member biasing the latch piece to rotate and move the said lug towards the pivotal mounting of the fuse tube, together with a movable member supported by the said other terminal and cooperable with the said lug to hold the fuse tube in closed circuit position without thereby imposing any strain upon the said fuse link except that caused by the said spring member.

5. In an electric fuse, two spaced insulated terminals, an expulsion fuse tube held by a pivotal mounting upon one of said terminals and held by a latch mechanism in contact with the other said terminal, and a fuse-link within the tube and completing the circuit therethrough; the said latch mechanism including a movable latch piece mounted on the fuse tube and with two lugs thereon, a movable hood mounted on the said other terminal and having a pair of holding parts under the hood and engageable with the said lugs to hold the fuse tube in closed circuit position.

6. In an electric fuse, two spaced insulated terminals, an expulsion fuse tube held by a pivotal mounting upon one of said terminals and held by a latch mechanism in contact with the other said terminal, and a fuse link within the tube and completing the circuit therethrough; the said latch mechanism including a movable latch piece mounted on the fuse tube and with two lugs thereon movable towards the pivotal mounting of the fuse tube, a hood mounted on the said other terminal, a pair of movable holding parts under the hood and engageable with the said lugs to hold the fuse tube in closed circuit position.

7. In an electric fuse, two spaced insulated terminals, an expulsion tube held by a pivotal mounting upon one of said terminals and held by a latch mechanism in contact with the other said terminal, and a fuse-link within the tube and completing the circuit therethrough; the said latch mechanism including a holding member supported upon the said other terminal, a latch piece pivotally mounted upon the fuse tube, a spring which biases the latch piece to rotate

about its pivotal mounting towards its releasing position, the said rotation being prevented by tension on the fuse-link, the said latch member and the said holding member when in normal closed circuit position engaging one another by pressure in a plane substantially transverse to the length of the tube.

8. In an electric fuse, two spaced insulated terminals, an expulsion fuse tube held by a pivotal mounting upon one of said terminals and held by a latch mechanism in contact with the other said terminal, and a fuse link within the

5 tube and completing the circuit therethrough; the said latch mechanism including a holding member mounted on the other said terminal, a latch piece movably supported on the tube and with a holding part that is engageable with the said holding member to keep the fuse in closed circuit position, the said holding part being biased towards the pivotal mounting of the tube and engaging the said holding part with pressure that is in a plane approximately transverse to the length of the expulsion tube.
